5. The process of claim 4 wherein R' and R'' are hydrogen.

6. The process of claim 4 wherein the catalyst is an alkyl iodide.

7. The process of claim 4 wherein the temperature is 50-150° C.

8. The process of claim 4 wherein R' and R'' are hydrogen, the alkyl halide is an alkyl iodide containing not more than 15 carbon atoms, the temperature is 25-200° C. and the reaction time is 1-10 days.

9. The process of claim 8 wherein R is C₂H₅—.

10. The process for making the oxazolidinone having the formula

5

10

15

comprising condensing the oxazoline having the formula

by contacting the oxazoline with ethyl iodide in an inert solvent at a temperature of 50-150° for a time of 1-10 days and separating from the reaction mixture the thus formed said oxazolidinone.

11. The process of claim 10 wherein the solvent is acetonitrile.

12. The process of claim 10 wherein the amount of ethyl iodide used is 1-25% by weight of the amount of oxazoline.
